UNITED STATES PATENT OFFICE.

THORNTON C. FRY, OF WYOMING, NEW JERSEY, ASSIGNOR TO WESTERN ELECTRIC COMPANY, INCORPORATED, OF NEW YORK, N. Y., A CORPORATION OF NEW YORK.

HARMONIC ANALYZER.

Application filed December 11, 1920. Serial No. 420,103.

To all whom it may concern:

Be it known that I, THORNTON C. FRY, a citizen of the United States, residing at Wyoming, in the county of Essex, State of New Jersey, have invented certain new and useful Improvements in Harmonic Analyzers, of which the following is a full, clear, concise, and exact description.

This invention relates to machines designed for the interpretation or analysis of plotted curves, and particularly to that class of machines commonly referred to as harmonic analyzers.

The object of this invention is to provide a machine which will enable a detailed study to be made of such curves, as those plotted to represent wave motions with far greater accuracy than is possible with the machines formerly in use.

Further objects of the invention are: to limit the movement of the tracing element to one direction only; to move the frame on which is placed the drawing carrying the curve to be analyzed, at right angles to the movement of said tracing element; to employ a constant source of power connected positively to said frame and also to a plurality of integrating mechanisms; and to associate said tracing element with the integrating mechanisms by suitable means.

The construction of the machine in accordance with the present invention will be more readily understood by reference to the drawings, in which Fig. 1 shows a plan view of the whole machine; Fig. 2 represents the side view; Fig. 3 shows an enlarged view of a portion of Fig. 2; Fig. 4 shows the means employed to register the relative movements of the machine; and Fig. 5 shows the device employed in tracing the plotted curve.

The mechanical construction of the machine will first be described. Mounted on one end of the iron base 6 is a motor 7 which is utilized as a source of power. At the other end of the base 6 is provided a frame 8, which is fitted with board 9 and adapted to receive the drawing paper 10 upon which the curve 11, to be interpreted, is drawn. Between the frame 8 and the motor 7 is situated a plurality of integrating and planimeter units. These will be hereinafter more fully described.

Enclosed within the gear box 12 are suitable gears to translate the motion imparted

to them from the motor 7 by means of shaft 13 to the shaft 14. The worm 15 on shaft 14 is adapted to engage spur gears 16 mounted on shaft 17 (see Fig. 3). The shaft 17 is provided with worms, such as 18 and 19, adapted to engage with worm gears 20 secured to vertical shafts. In Fig. 3 one of these worm gears 20 is represented as being attached to the shaft 21. The shaft 21 is provided with bearings 22 secured to the frame 23, said frame being vertically mounted in any suitable manner upon the base 6. Collar 24 is utilized to prevent vertical displacement of the shaft 21. At the upper end of the shaft 21 are mounted two gears 25 and 26, adapted to engage gears 27 and 28 respectively. The rotation of these gears is communicated by means of shafts 29 and 30 to intermediate gears 31 and 32. These gears are detachably mounted upon their respective shafts in order that they may be replaced by other interchangeable gears adapted to be mounted in suitable position for engagement with any of the series of gears shown at 33 and 34 respectively. The motion received by any one of the gears belonging to, say the series represented by 33, is imparted to the frame 35, which causes the sphere 36, mounted therein, to revolve about its vertical axis. The spheres 36 rest on discs 37 which are secured to shafts 38. The shafts 38 are adapted to be rotated by the frictional engagement between belt 39 and pulleys 40, as will be described in greater detail hereinafter. Attached to the frame 35 are two sets of integrating apparatus, whose exact location as regards the sphere will be more readily seen by reference to Fig. 4.

In Fig. 4 sphere 36 is represented as being in contact with three discs 41, 42 and 43. The disc 41 is used in order to secure the sphere in an absolutely correct position and yet render it free to move about either axis. It is used, in other words, merely as a guide. It will be noted that discs 42 and 43 are adapted to operate similar mechanisms, but that they are in engagement with the sphere at right angles to each other. Considering the mechanism associated with disc 42, for the purpose of illustration, it will be seen that the motion imparted thereto from the sphere 36 is communicated directly to the shaft 44 upon which is placed the graduated wheel 45. The pointer 46 is used to more

clearly indicate the relative turning of the wheel 45. In order to obtain a more accurate reading than the graduations on 45 will permit, the scales 47 and 48 are provided. The motion of shaft 44 is imparted to a series of gears 49 by means of the worm 50, thus indicating any fractional displacement not recorded by the wheel 45.

The plan view, as shown in Fig. 1, represents ten separate units, such as have just been described, and are numbered 101, 102, 103, 104, 105, 106, 107, 108, 109, and 110. The only difference in the construction of these units is in the size of the gears making up the series 33, 34, etc.

Shaft 14, which is adapted to be actuated by the motor 7 through the series of gears contained in case 12, and which is adapted to actuate the integrating mechanism, as already hereinabove described, is in addition utilized to impart a horizontal motion to the frame 8 by means of the spur gear 51. The base 6 is provided with two parallel grooved tracks 52 and 53 in which rollers 54 and 55, attached to the frame 8, are adapted to move. Mounted on base 6, free and clear of the movable frame 8, are pieces 56 and 57 to which parallel bars 58 and 59 are secured. These bars act as a guide for the tracer 60, which is most clearly shown in Fig. 5. The construction of the tracer 60 is extremely simple, the handle 61 being provided in order that motion may be imparted to said tracer by the hand of the operator.

The two pulley wheels 62 and 63 are so spaced that they will fit readily between the guide bars 58 and 59. The pointer 64 is adapted to engage with the plotted curve to be interpreted and, therefore, is made as pointed as the accuracy of the machine as a whole warrants. Lug 65 is provided with a hole through which belt 39 slidably passes, while lug 66 is so constructed as to permit of a permanent connection between it and belt 39. Belt 39 also passes around pulley 67, which is so mounted on piece 57 that it may be moved either to the left or right according to whether or not belt 39 is excessively tight or loose.

It will be noted from the above description that in tracing out curve 11, the motor causes the board to move under the tracer 60 along the so-called X axis. The operator, with his hand on the tracer, causes it to move along the Y axis a sufficient amount to enable the point 64 to continuously engage the curve 11. The motion of the tracer 60 is imparted to shafts 38 by means of belt 39 and pulleys 40, said motion thus being imparted to the spheres 36 through the agency of discs 37. Thus these spheres are rotated about a horizontal axis. Simultaneously with this movement, the sphere is also rotated about its vertical axis by virtue of the motion communicated to it from the motor

through shafts 14, 21 and frame 35, and the gears associated therewith.

The diameter of the gears constituting series 33, 34, etc. and the gears corresponding to 31, 32, etc., bear a definite relation to the wave length of the curve 11, as drawn. Thus, the lowest gear of these series associated with unit 101, is of such a diameter that when the intermediate gear, similar to 31, 32, etc. is placed in engagement therewith, it will make one complete rotation while the tracer is moved one wave length. In like manner, the lowest gear of the series associated with 102 is of such a diameter that when in engagement with its intermediate gear it will make two complete rotations while the tracer moves the same distance. Similarly, the lowest gears in units 103 to 110 will rotate three to ten times respectively, under the same conditions. The second gear associated with unit 101, when engaged will rotate eleven times; that of unit 102, 12 times, and so on. It will, therefore, be apparent that the top gear of unit 110, when engaged, will rotate one hundred times, while the tracer moves over one wave length. By placing the intermediate gears in engagement with the lowest gears of each unit, the spheres 37 associated therewith will be rotated upon tracing over the curve 11 once, as follows:

Unit 101, once,
Unit 102, twice, etc.

Or, if it is desired to rotate the spheres from eleven to twenty times, the gears immediately above the lowest pulleys would be engaged by the several intermediate gears. It can readily be seen that many different combinations of rotations may be had by adjusting the intermediate gears.

Although one specific arrangement of the gears associated with each unit has been described, it may be that the specific problem at hand will require a different disposition of them. It is not intended, therefore, to limit the present invention to the exact positioning of the different gears.

The method of operating the machine will now be described. For the sake of clearness, it will be assumed that the specific problem at hand is the analysis of a periodic electrical wave into its various harmonics. It is to be understood that this machine is not limited to the interpretation of electrical waves, but may be utilized in the analysis of other wave motions, such as sound, light, etc., or in obtaining the trigonometric series expansion of any portion of any curve whatsoever, regardless of the origin or significance of said curve.

The periodic wave is first drawn on suitable paper in such a manner that a complete wave length will cover exactly a given distance. For purpose of reference, we will

assume that for the particular machine shown herein, this distance is "T." There is no limit to the other dimensions of the curve save that it must, of course, be such that the whole curve is on the paper. The diagram should be placed, as indicated in Fig. 1, i. e. so that the axis of the curve is perpendicular to the guide bars 58 and 59. The tracer 60 is moved along the guide bars

58 and 59 until its pointer 64 touches the 10 curve 11, where it intercepts the X axis, i. e. the axis of the curve itself. The three scales of both recording mechanisms associated with each of the ten spheres are adjusted to give zero readings.

15

Now, curve 11 being a periodic wave, it may be expressed according to Fourier's theorem, as follows:

$$y = A_0 + A_1 \sin \frac{2\pi t}{T} + A_2 \frac{4\pi t}{T} + \dots + A_n \sin \frac{2n\pi t}{T} + B_1 \cos \frac{2\pi t}{T} + B_2 \cos \frac{4\pi t}{T} + \dots + B_n \cos \frac{2n\pi t}{T}$$

Where; "T" is the wave length; n the 20 number of cycles of sine or cosine waves during one cycle of the original curve; t the elapsed time reckoned from any instant and A_1 to A_n and B_1 to B_n are the coefficients which must be determined by integration. 25 In case the curve is not periodic, any portion of it, of length T , may be so expressed. The term A is given by the formula

$$A_0 = \frac{1}{T} \int_0^T y dt,$$

30 and must be separately determined. Moreover, as the curve 11 has neither the kind of symmetry to the Y axis as is possessed by sine or cosine curves, it is resolvable into a series of sine curves and a series of cosine curves. 35 However, when the electrical waves which occur in practice have only odd harmonics, the terms signifying the even ones in the above equation may be dispensed with.

40 The various coefficients A_1 , A_2 , etc., A_n , and B_1 , B_2 etc., B_n are the quantities to be determined by the machine which forms the subject of the present invention. These coefficients may be expressed as follows:

$$45 A_n = \frac{2}{T} \int_0^T y \sin \frac{2\pi nt}{T} dt$$

and

$$50 B_n = \frac{2}{T} \int_0^T y \cos \frac{2\pi nt}{T} dt$$

The function of the machine is, therefore, to perform the above integration. The "A" integrations are read from the recording mechanism associated with disc 42, and the 55 "B" integrations from that associated with disc 43.

From the statement of Fourier's theorem, as given above, it will be apparent why the 60 present machine makes use of such motions as have already been described. The X and Y values of the given curve 11 appear in the Fourier series as angular quantities, and such transformation may readily be secured by compounding the motions as have heretofore been described. When the pointer has been moved along the curve 11 a distance of dy and the plane of disc 42 is at an angle $n\theta$ with the X or time axis, the sphere 36 will be turned, by the motion im-

parted to it from the motor 7, an amount 70 proportional to dy , and such movement will be registered by both 42 and 43. If the radius of sphere 36 be r , the point of contact between disc 42 and sphere 36 will be at a distance $r \sin n\theta$ from the axis of sphere 75 36 and the motion of disc 42 will be proportional to $dy \sin n\theta$. In like manner the motion of disc 43 will be proportional to $dy \cos n\theta$. It will be apparent then that when pointer 64 moved over the entire curve 11, so the numbers registered by discs 42 and 43 will be proportional to the coefficients as expressed in Fourier's series, i. e. A_n and B_n . The dimensions of the parts are so chosen that these readings will give A_n and B_n in 85 centimeters. Thus it is clear that as the pointer 64 traces out the curve, each dy is multiplied by sine $n\theta$ or cos $n\theta$ which is effected by the machine by converting dy into two components at right angles to each 90 other, one of which is at an angle of $n\theta$ with the X or time axis.

The relation between the given curve 11 and that transcribed by any given point of the sphere 36, such as for example the point of contact between the sphere 36 and the disc 42 may be readily shown by constructing a curve using as ordinates $r \sin n\theta$ and $r \cos n\theta$. The lines drawn from the end of such curve to the origin of the 95 diagram will make an angle with the Y axis, which will be designated α_n . If we then assume some quantity such as Z_n which has the following relation to A_n , B_n , and

$$A_n = Z_n \cos \alpha_n \\ B_n = Z_n \sin \alpha_n \\ Z_n^2 = A_n^2 + B_n^2$$

105 The Fourier series may be expanded thus: 110

$$y = Z_1 \sin (\theta - \alpha_1) + Z_2 \sin (2\theta - \alpha_2) \\ Z_n \sin (n\theta - \alpha_n).$$

The line above referred to as being drawn from the origin of the diagram to the end 115 of the curve will then be Z_1 . If, now, the axis of the sphere 36 makes n turns while the pointer 64 moves over one complete period of the curve 11, the value of the line above referred to will become $n Z_1$ and it 120

will make an angle of Z_n with the Y axis. By utilizing the entire set of ten spheres provided in this machine, together with its associated gears, the values of C_n and α_n 5 up to $n=100$ may be determined.

While a specific construction is described hereinabove, it is to be understood that it is intended to cover any obvious modifications of same, which come within the scope 10 of the appended claims.

What is claimed is:

1. A harmonic analyzer comprising a base member, a movable frame and a plurality of integrating mechanisms mounted on said 15 base member, and a source of power connected with said frame and mechanisms for imparting motion thereto.

2. A harmonic analyzer comprising a plurality of integrating mechanisms each of 20 said mechanisms consisting of a sphere associated with means adapted to rotate said sphere about its vertical axis, and means adapted to rotate said sphere about its horizontal axis, said first mentioned means being 25 actuated by a constant source of power.

3. A harmonic analyzer comprising a base member, a movable frame mounted on said base member and adapted to carry the paper upon which the curve to be integrated is 30 drawn, a plurality of integrating devices mounted on said base member, and common means for actuating said integrating devices and said frame.

4. A harmonic analyzer comprising a 35 movable frame, a plurality of spheres, means for rotating said spheres upon their vertical axes, and a common source of power adapted to impart motion to said frame and spheres whereby said spheres are caused to rotate 40 upon their horizontal axes.

5. A harmonic analyzer comprising a 45 movable frame, a plurality of integrating mechanisms having different speeds of rotation, a movable tracing element, said frame and said tracing element adapted to be moved at right angles to each other, a source of power connected with said frame and said mechanisms for imparting motion thereto, and means controlled by said tracing element for actuating said integrating mechanisms. 50

6. A harmonic analyzer comprising a 55 movable frame, a plurality of integrating mechanisms having different speeds of rotation, two horizontally disposed guides, a tracing element adapted to be moved between said guides over said frame, a source of power connected with said frame and said mechanisms for imparting motion thereto, and means associated with said tracing element for imparting motion to said integrating mechanisms. 60

7. A harmonic analyzer comprising a 65 movable frame, a plurality of integrating mechanisms having different speeds of rota-

tion, a tracing element cooperating with said frame, means for imparting motion to said integrating mechanisms and said frame, and means for communicating motion imparted to said tracing element to said integrating 70 mechanisms.

8. A harmonic analyzer comprising a frame, a plurality of integrating mechanisms having different speeds of rotation, a tracing element adapted to cooperate with 75 said frame, a motor to impart motion to said integrating mechanisms and to said frame, and means adapted to communicate motion imparted to said tracing element to said integrating mechanisms. 80

9. A harmonic analyzer comprising a movable frame, a plurality of integrating mechanisms having different speeds of rotation, means common to said frame and said integrating mechanisms for imparting motion thereto, and means adapted to vary the relative movements of said frame and said integrating mechanisms. 85

10. A harmonic analyzer comprising a movable frame, a plurality of integrating 90 mechanisms having different speeds of rotation, each of said mechanisms consisting of a sphere associated with means adapted for rotating said sphere upon its vertical axis, and means for imparting motion to said movable frame and to said integrating mechanisms whereby said spheres are caused to rotate upon their horizontal axes. 95

11. A harmonic analyzer comprising an 100 integrating mechanism including a sphere, means for revolving said sphere upon its vertical axis, means for moving said sphere upon its horizontal axis, a disc associated with said sphere, and a recording mechanism associated with said disc. 105

12. A harmonic analyzer comprising a 110 movable frame, a plurality of integrating mechanisms having different speeds of rotation, a motor, a shaft driven by said motor, and a series of gears adapted to be associated with said shaft as desired to impart motion thereto, said shaft communicating to said mechanisms the motion of said movable frame.

13. A harmonic analyzer comprising a 115 series of gears of varying diameters, an integrating mechanism comprising a sphere associated therewith, a shaft adapted to mount interchangeable gears of varying sizes for engaging said gears, and means for imparting motion to said last mentioned shaft.

14. A harmonic analyzer comprising a 120 movable frame, a source of power associated therewith, a series of gears of varying diameters associated therewith, a vertical shaft adapted to mount one of a series of interchangeable gears adapted, respectively, to engage any one of said series of gears, and an integrating mechanism including a 125 130

- sphere driven by each of said first mentioned series of gears.
15. A harmonic analyzer comprising an integrating mechanism including a sphere, 5 a pair of guides in spaced relation, a tracing element adapted to be moved between said guides and in contact with said movable frame, a disc contacting with said sphere, and means for communicating to said disc 10 the motion imparted to said tracing element.
16. A harmonic analyzer comprising a movable frame, a source of power associated therewith, a series of gears associated therewith, an integrating mechanism associated 15 with said gears, a shaft provided with a worm gear, and a second worm gear located on a shaft disposed at right angles to said first-named shaft, said second-named shaft adapted to impart motion communicated 20 thereto to said integrating mechanism.
17. A harmonic analyzer comprising a motor, a series of gears associated therewith, a plurality of integrating mechanisms having different speeds of rotation associated with said gears, a shaft provided with 25 a worm gear associated with said series of gears, and a second worm gear located on a shaft disposed at right angles to said first mentioned shaft, said second mentioned shaft adapted to impart motion communicated 30 thereto to said integrating mechanisms.
18. A harmonic analyzer comprising a movable frame, a plurality of integrating 35 mechanisms having different speeds of rotation, a pair of guides in spaced relation, a tracing element adapted to be moved between said guides and in contact with said movable frame, means for causing the relative movement of said frame and said tracing element at right angles to each other, and means controlled by said tracing element for actuating said integrating mechanisms.
- 40 19. A harmonic analyzer comprising an integrating mechanism including a sphere, means for revolving said sphere upon its vertical axis, actuating mechanism comprising a plurality of gears and shafts, a disc 45 associated with said actuating mechanism and cooperating with said sphere, and an indicating mechanism associated with said disc.
20. A harmonic analyzer comprising a motor, a series of gears associated therewith, 55 a movable frame actuated by said motor, a plurality of integrating mechanisms having different speeds of rotation associated with said gears, a shaft provided with a worm gear associated with said series of gears, a second worm gear located on a shaft disposed at right angles to said first mentioned shaft, said second mentioned shaft adapted to impart motion communicated 60 thereto to said integrating mechanisms, an indicating mechanism associated with each of said integrating mechanisms, and means associated with said integrating mechanisms for actuating the respective indicating mechanisms. 65
21. A harmonic analyzer comprising a movable frame adapted to carry the paper upon which the curve to be integrated is drawn, a plurality of integrating devices having different speeds of rotation, common 70 means for actuating said integrating devices and said frame, a plurality of indicating mechanisms, and means associated with each of said integrating devices for actuating one of said indicating mechanisms. 75
22. A harmonic analyzer comprising a movable frame, a plurality of spheres, means for rotating said spheres upon their vertical axes, a common source of power adapted to impart motion to said frame and 80 spheres whereby said spheres are caused to rotate upon their horizontal axes, a plurality of indicating mechanisms, a disc associated with each of said spheres and adapted to impart to said indicating mechanisms the motion communicated to said spheres, and means for adjusting the relative movements 85 of said frame and said spheres. 90

In witness whereof, I hereunto subscribe my name this 4th day of December A. D. 90
1920.

THORNTON C. FRY.
